Primary Examiner — Karen S Acker(74) Attorney, Agent, or Firm — Brent Globerman, LLCCLAIM

I claim the ornamental design for a football shaped flag, as shown and described.

DESCRIPTION

FIG. 1 is a perspective view of a flag embodying the design of the present invention.

FIG. 2 is a front view of the flag shown in FIG. 1.

FIG. 3 is a back view of the flag shown in FIG. 1.

FIG. 4 is a right side view of the flag shown in FIG. 1.

FIG. 5 is a left side view of the flag shown in FIG. 1.

FIG. 6 is a top view of the flag shown in FIG. 1.

The broken lines in the drawings represent unclaimed environmental subject matter and form no part of the claimed design.
